Specification of Letters Patent. Patented Aug. 22, 1916.

Original application filed June 16, 1910, Serial No. 567,128. Patent No. 1,114,085, dated October 20, 1914.
Divided and this application filed December 2, 1913. Serial No. 804,159.

To all whom it may concern:

Be it known that I, GEORGE WHITE, a citizen of the United States, residing at Jersey City, in the county of Hudson and State 5 of New Jersey, have invented certain new and useful Improvements in Filing-Cabinets, of which the following is a specification, reference being had therein to the accompanying drawings, which form a part 10 thereof.

My invention relates to filing cabinets and more particularly to a type thereof adapted for use in connection with a register of the type described in my application for Letters Patent Serial No. 567,128, filed June 16, 15 1910, which eventuated in Letters Patent No. 1,114,085, dated October 20, 1914, this being a division of said application.

The main object of my invention is to provide a filing cabinet embodying therein a plurality of filing devices each of which is mounted in a supporting casing in a manner to prevent the complete removal thereof, independently operative means being 20 provided whereby said devices may all be simultaneously locked and any open device will be automatically closed with the actuation of the locking means.

A further object is to provide a cabinet 30 provided with closing and locking means of the character above referred to, which may be built of a plurality of separable sections each containing a plurality of filing devices, to permit the dismantling of the 35 cabinet to permit the storing of the files in a fire-proof safe or vault, or for any other purpose.

A still further object is to provide a filing cabinet of the character above referred to, 40 wherein the several filing devices are normally closed and locked by means common to all of such devices, said means being under the control of the locking mechanism and being capable, when released, of being 45 operated by the movement of any filing device to prevent the resetting of the locking means except at the will of the operator.

A still further object is to provide a cabinet 50 embodying a plurality of independently slidable drawers adapted to be automatically closed by the actuation of the locking mechanism, each said drawer having a plurality of filing compartments provided, sev-

erally, with a normally closed and independently movable cover so arranged that 55 with the closing of the drawer the cover will be automatically closed and latched, thus permitting access to any file without exposing the contents of other files contained in the drawer, and eliminating possibility 60 of the jamming of the drawer in closing, through the raised cover. And a still further object is to provide a cabinet of this character, the operative mechanism of which will be simple in design and easy of operation. 65

The invention consists in the novel features of construction and combination of parts hereinafter set forth and described and more particularly pointed out in the 70 claims hereto appended.

Referring to the drawings: Figure 1 is a perspective view of a register showing the application of my invention thereto; Fig. 2 is a perspective view of one of the sections 75 removed from the main casing; Fig. 3 is a horizontal view, partly broken away, of one of the drawer sections, showing a plan view of the locking means; and, Fig. 4 is a side elevation of said locking means. 80

Like letters refer to like parts throughout the several views.

In the embodiment of my invention shown in the drawings, I have shown at 1 a casing, preferably made of sheet metal, which casing has mounted therein, by means of the grooves 2, a plurality of superposed independent casings 3, adapted to be secured relative to the casing 1 in any desired manner, as by hinged side strips 4. The casings 3 have slidably mounted therein a plurality of slidable drawers 5, which are permanently secured in said casings in a manner to permit that relative movement thereof necessary to expose that portion of the 95 drawers 5 containing the matter to which access is desired, or in which it is desired to file a record, while not permitting the complete withdrawal of the drawer. Each drawer 5, contains a plurality of compartments, formed by the partitions 6, and each compartment is closed by a hinged cover 7, adapted to be secured in the closed position by a spring latch 8. The hinged connection between the drawer 5 and its cover 100 7 is adjacent to the rear of the compart- 105

ment and embodies therein a spring 9 tending to normally raise the said cover. The location of this hinge is such that with the closing of the drawer the cover 7 will be forced downwardly by engagement with the top of the casings 3, or with the drawer immediately above. This arrangement is important as it permits the association of a large number of filing compartments, a plurality of which may be exposed at one time without exposing the contents of any other compartment unless desired. The primary object of a cabinet of this kind is for use in connection with a system of charge accounts wherein the purchaser could readily see the contents of any cabinet drawer and secure information as to other charge accounts which would be undesirable, were not the independently movable, normally closed covers provided for the separate compartments.

Mounted in the casing 1 rearwardly of the casings 3 are a plurality of vibratory or oscillatory rods 10, carried by the arms 11 25 12, one disposed at the bottom and the other at the top of said casing 1, so as to insure rigidity in the rods 10. One set of said arms is arranged upon each side of the longitudinal center of the casings 1 and 3, and 30 said rods respectively rotate about a fixed axis 13, under the control of the reciprocatory rack frame 14, and the segmental racks 15 connected to the rods 16, carrying the arms 11 and 12.

35 Each drawer 5 has nested in the rear portion thereof, a lever system adapted to operate with the rods 10 in permitting the opening of any drawer and insure the closing thereof with the actuation of said rods. 40 This lever system may also be utilized to secure each drawer relative to its casing 3, allowing that limited movement necessary to fully expose the several drawer compartments.

45 Each casing 3 carries a fixed vertical pivot 17 upon which is mounted a plurality of levers 18, 19, the short arms of which project across a recess, 20, in the rear of said casing, and the long arms of which are connected by means of the links 21 with the drawer 5, said means of connection with the drawer being provided to compensate for the arc described by the levers 18, 19. The rods 10, being common to all drawers 5, are 50 adapted to enter the recesses 20 in each casing 3, and engage the short arms of the levers 18, 19 of each drawer, which levers act as lazy tongs with the opening of a drawer or the actuation of the rods 10.

55 The rack frame 14 is provided with means as the extension 22, whereby it may be positively reciprocated at the will of the operator, and said frame is provided with means whereby it may be locked after it has been actuated to close the several drawers. This

latch mechanism preferably consists of a gravity pawl 23 carrying a bolt 24 adapted to enter the socket 25 in the frame 14. This pawl is under the control of a movable cam 26 which may be actuated in any desired manner, the pawl 23 being held in the proper operative relation to the cam 26 by the stop 27.

The operation of the herein described filing cabinet is substantially as follows:— 75 Normally the frame 14 is held against movement by the bolt 24 of the pawl 23, the rods 10 being pressed against the short arms of the levers 18, 19 thus preventing any movement of any of the drawers 3. 80 When it is desired to gain access to any drawer the latch mechanism controlling the frame 14 is released, by disengaging the pawl 23 and the cam 26, thus permitting the said frame to move freely in either direction. The frame 14 thus being released, any drawer 5 may be opened to the extent defined by the lazy tong connection with the casing 3, the short arms of the levers 18, 19, through their engagement with the rods 10, reciprocating the frame 14 and so positioning the said levers as to cause a return movement thereof to restore the levers 18, 19 to normal and automatically close the drawer. The drawer being opened, access 95 may be had to any compartment therein by merely releasing the spring latch 8, the cover 7 of that particular compartment immediately springing upward under its spring hinge 9, and remaining in the open 100 position without, however exposing the contents of any other compartment in that drawer. The frame 14 being thus released, access may be had to any drawer, or to any sequence of drawers, without actuating said 105 frame, any drawer being capable of being closed independently of the rods 10 as well as therethrough. When it is desired to again lock the cabinet, the frame 14 is returned to its normal position through the 110 actuation of the extension 22 thereof, in any desired manner, this movement of said frame thrusting the rods 10 against the short arms of the levers 18, 19 and oscillating said levers, thus pulling the drawer 5 within its 115 casing 3 through the links 21. Thereafter the pawl 23 is raised by means of the cam 26, to cause the bolt 24 to enter the socket 25. The rods 10 being common to all 120 drawers 5, their oscillation will automatically close any open drawer, and the means preventing a movement of said rods will lock all drawers in this closed position.

A plurality of drawers 5 being mounted in each casing 3, and a plurality of said casings 3 being removably retained in the outer casing, the files may be removed whenever desired and stored in a safe, fire-proof vault, or in any other desired place or manner. For convenience each casing 3 should ap- 125 130

proximate in size, an ordinary day-book or ledger, as shown in Fig. 2. This arrangement also permits the extension of the cabinet system as desired.

- 5 As any drawer 5 is closed under the control of the levers 18 19, or manually, that portion of the cover 7 adjacent to the hinge will engage the top of the casing 3 or bottom of the drawer immediately above the 10 open drawer and automatically close and latch said cover. This construction is desirable as avoiding any possibility of any drawer becoming jammed through a misplaced cover.
- 15 The form of the invention shown in the accompanying drawings is designed especially for use in connection with a special type of machine wherein the latch pawl 23 and the frame 14 will be automatically actuated, but the design of the mechanism may be varied to adapt it for use in other connections without departing from the spirit or scope of the invention.

I am aware that it is not new in the arts 25 to provide filing cabinets made up of a plurality of separable sections, or to provide means simultaneously locking a plurality of slidable drawers, but I believe it to be broadly new, however, to provide means for 30 automatically closing and locking a drawer or series of drawers by a single mechanism.

Having described my invention, what I claim as new and desire to have protected by Letters Patent is:—

- 35 1. In a filing cabinet, a casing, filing devices mounted therein, a vibratory member, a latch member adapted to control the movement of said vibratory member, and means carried by said filing devices and co-operating with said vibratory member whereby the actuation of said vibratory member in one direction will permit said filing devices to be opened, and its actuation in the other direction will close said filing devices.
- 40 2. In a filing cabinet, a casing, filing devices mounted therein, means securing said devices in said casing while permitting a limited movement thereof, a vibratory member, a latch member adapted to control the movement of said vibratory member, and means carried by said filing devices and co-operating with said vibratory member whereby the actuation of said vibratory member in one direction will permit said filing devices to be opened, and its actuation in the other direction will close said filing devices.
- 45 3. In a filing cabinet, a casing, a drawer slidably mounted therein, a lever pivoted to said casing, means whereby one arm of said lever is connected to said drawer to compensate for the pivotal movement of said lever, and the other arm of said lever being adapted to be projected beyond said casing, and a vibratory member adapted to engage
- 50 said last mentioned lever arm, whereby the

actuation of said member in one direction will permit said drawer to be opened, and its actuation in the other direction will close said drawer.

4. In a filing cabinet, a casing, a drawer 70 slidably mounted therein, a lever pivoted to said casing, means whereby one arm of said lever is connected to said drawer to compensate for the pivotal movement of said lever, and the other arm of said lever being adapted to be projected beyond said casing, a reciprocatory rack frame, a segmental rack meshing therewith, an arm actuated by said segmental rack, a rod adapted to engage the short arm of said lever carried by said arm, 80 whereby the movement of said frame in one direction will permit said drawer to be opened and its movement in the other direction will close said drawer, and means whereby said frame may be locked against 85 movement.

5. In a filing cabinet, a plurality of superposed separable casings, a plurality of sliding drawers in each of said casings, means connecting each of said drawers to its casing, said means permitting limited movement of the drawer relative to its casing, means operative upon said last named means whereby any open drawer may be closed and all said drawers may be simultaneously locked in the closed position, and means securing said casings relative to each other.

6. In a filing cabinet, a plurality of superposed separable casings, a plurality of sliding drawers in each of said casings, each of said drawers being provided with a lever pivoted to its casing, and means whereby one arm of said lever is connected to said drawer to compensate for the pivotal movement of said lever and the other arm of said lever being adapted to be projected beyond said casing, and a vibratory member common to all of said levers and adapted to engage with the said last mentioned lever arm whereby the actuation of said member in one direction will permit any of said drawers to be opened, and its actuation in the other direction will close any open drawer.

7. In a filing cabinet, an outer casing having mounted therein a reciprocatory frame, a plurality of oscillatory members adapted to be actuated by said frame, a rod carried by each of said oscillatory members, extending substantially throughout the entire height of the said casing, means whereby said frame may be reciprocated, means whereby said frame may be locked against reciprocation, and a plurality of superposed separable casings mounted by a tongue and groove connection in said first named casing, each of said casings having slidably mounted therein a plurality of drawers, each drawer being provided with a lazy tong 120

connection with its sectional casing, said rods being common to all of said tongs, whereby the movement of said frame in one direction will permit any drawer to be 5 opened and its movement in the other direction will close any open drawer.

In witness whereof, I have hereunto af-

fixed my signature in the presence of two witnesses, this 17th day of July, 1913.

GEORGE WHITE.
